HYDROCARBON BURNER

Basil V. Szabó, Jamaica, N. Y., assignor of forty
percent to Wilfred C. Rasmussen, New York,
N. Y.

Application February 9, 1934, Serial No. 710,507

6 Claims. (Cl. 158—28)

This invention relates to hydrocarbon burners and to systems for supplying fuel to the burners. More particularly, it relates to burners of the type in which an atomized fuel obtained, for example, by mixing a liquid such as oil with a gas under pressure, is vaporized by being heated before being burned. The invention is especially applicable to oil furnaces for residential or industrial use, to oil stoves and heaters, and to various other types of burners of hydrocarbonous fuels. The principles outlined hereinafter are also applicable to the production of vaporized fuels for various other purposes.

A primary object of the invention is to provide a hydrocarbon burner in which complete combustion of the fuel is obtained in an efficient manner.

Another and equally important object of the invention is to provide a system for supplying fuel to the burner which will insure complete atomization of the fuel, and which will permit the atomized fuel to be readily controlled.

Another object of the invention is to provide means for effectively isolating the combustion zone of the burner from other parts thereof and to thereby prevent backfiring.

Still another object of the invention is the provision of means between the combustion zone of the burner and the fuel mixing chamber which permits the free passage of fuel therethrough and prevents the atomized fuel from being burned before passing therethrough.

A still further object of the invention is the provision of means for heating the atomized fuel before it passes into the combustion zone.

Another object of the invention is to remove the fuel heating means so far from the atomizer that the nozzle of the atomizer is kept at such a low temperature that the formation of gum and carbon deposits are eliminated.

Another object of the invention is to provide an efficient device for the carbureting of oils, to provide suitable vaporized fuels for all purposes.

Other objects of the invention will become apparent upon reading the following specification and appended claims in connection with the accompanying drawings, which illustrate an approved form of apparatus embodying the invention.

In the drawings Fig. 1 is a sectional view of a hydrocarbon burner constructed in accordance with the principles of the invention.

Fig. 2 is a sectional view of a part of the burner illustrated in Fig. 1.

Fig. 3 is a top view of the heat conducting member illustrated in Fig. 2.

Fig. 4 is a diagrammatic illustration showing the burner illustrated in Fig. 1, and the fuel supply system for the burner.

Fig. 5 is a plan view of a modified form of one of the elements of the burner.

Fig. 6 is a sectional view taken on line 6—6 of Fig. 5.

Fig. 7 is a plan view of another element of the burner, and

Fig. 8 is a sectional view taken on line 8—8 of Fig. 7.

The hydrocarbon burner illustrated in Fig. 1 consists essentially of an atomizer 10, a fuel mixing tube 11 through which the atomized fuel is sprayed, a heater 12 for heating the atomized fuel and a screen 13 through which the heated fuel passes to the zone indicated generally at 14 where combustion occurs. The burner also includes an automatic system indicated generally at 15, for shutting off the fuel supply when the fuel is not being properly atomized and burned.

The atomizer 10 comprises a device in which a liquid fuel under pressure is mixed with air, steam or any suitable gas under pressure for the purpose of providing a spray of finely divided fuel particles. The fuel is supplied to the atomizer by means of a pipe 16 and the air or other gas, or steam is supplied by means of a pipe 17. The manner in which the fuel and air are supplied to the atomizer and the pressure at which they are maintained will be set forth in more detail hereinafter.

The atomizer includes a member 18 which constitutes a valve and valve stem. The valve member 18 is threaded into but spaced for part of its length from a tubular member 19 by suitable means such as lugs 19' provided on the valve member. The space between the valve member 18 and the tubular member 19 forms a duct or annular channel 20. The fuel supply pipe 16 is connected with the member 19 or with any other suitable part of the atomizer in such a way that fuel is supplied to the duct or annular channel 20. The lugs 19' may be inclined at an angle to the vertical axis of the member 18 for the purpose of imparting a rotary motion to the oil as it flows through the annular channel 20.

One end of the tubular member 19 is closed by the valve member 18 and the other end is provided with a cap 21 which terminates in a conical head. The apex of the conical head is provided with an orifice 22 communicating with the annular channel 20.

The tubular member 18 is housed within a hollow cylindrical member 23 and spaced therefrom by suitable lugs 21' to form a second duct or annular channel 24. The member 23 has an internal conical surface adjacent the conical head on the cap 21 and it is movable longitudinally to vary the space between its internal conical surface and the conical head of the cap 21. A suitable lock nut 23' holds the member 23 in place and seals the joint between member 23 and the body of the atomizer 10. The spacing lugs 21' may also be inclined to impart a rotary or twisting motion to the air in channel 24. The angles at which the lugs 19' and 21' are arranged and the direction in which they are inclined, are such as to give the most satisfactory atomization of the fuel. The air supply pipe 17 is connected to the atomizer in any suitable manner to supply air under pressure to the annular channel 24. The air duct 24 terminates in an elongated bore or passageway having an orifice 25 at the end thereof. The passageway is aligned with the orifice 22. The orifice 22 connects the oil duct 20 with the air duct 24.

Oil or other fuel under pressure is supplied through the pipe line 16 to the annular channel 20 and forced through the comparatively small orifice 22 into the elongated passageway. At the same time compressed air is forced through the outer channel 24 into the bore or passageway where it mixes with the oil and breaks the oil up into small particles. These finely divided particles are sprayed from the orifice 25 as indicated by the spray 26.

A valve 27 is located in the elongated passageway to control the flow of atomized fuel and air therethrough. The valve 27 may be operated manually and/or automatically. A more satisfactory control of the fuel supply is obtained by locating the valve in the path of the atomized mixture and thus controlling the flow of the mixture after atomization occurs, than is obtained when either the fuel or the air supply is controlled separately.

The valve member 18 is provided with an axial bore adapted to receive a rod 28. One end of the rod is located inside the valve member 18 at the end thereof adjacent the orifice 22. The rod extends through the valve member and terminates in a knob 28'. A spring 29 arranged to bear against a shoulder on the rod holds the rod in the position shown. The orifice 22 may be cleaned by pressing against the knob 28' and forcing the other end of the rod through the orifice. The rod which is just large enough to pass through the orifice, may be made long enough to also pass through the orifice 25 when the knob 28' is pressed.

A handle 30 is secured to the valve member 18 for the purpose of screwing the valve member into or out of the tubular member 19 and thereby by moving the valve 18 toward or away from the valve seat 18' to regulate the flow of fuel into the annular chamber 20.

The atomized fuel spray 26 is directed through a mixing tube 11 which is constricted as at 31. The velocity of the fuel particles is increased at the constricted portion and this creates a suction which draws in auxiliary air to mix with the atomized fuel. The mixing tube 11 is housed within but spaced from the outer shell 32 of the burner. The bottom of the shell 32 is supported on a suitable frame 33 which also supports the atomizer 10 and the mixing tube 11. The frame

is open in order that the auxiliary air may be drawn into the mixing tube 11.

The spray of atomized fuel 26 is directed against the heater 12. The heater which is located at the top of the shell 32, conducts heat from the combustion zone 14 to the atomized particles of fuel. The heater raises the temperature of the fuel until the atomized particles are vaporized. The fuel vapors pass through the screen 13 and are burned in the combustion zone 10 directly above the screen.

The heater 12 is shown in more detail in Figs. 2, 3, 7 and 8. It consists of a deflector 34, a heat conducting member 35 adjustably threaded in the deflector 34, a rim 36 and a plurality of heating 15 arms 37 extending between the rim and the deflector. The heater is held in place in any suitable manner such as by securing the rim 36 to the top of the casing 32.

The heater is preferably provided with a large 20 number of arms 37 in order that they may be sufficiently near each other to thoroughly vaporize all the atomized fuel. The arms may be radial as shown, or they may be spiral or have any other desired shape. The arms may have 25 any desired cross section which will insure satisfactory heating of the atomized fuel. In some instances it may be found desirable to substitute a perforated plate or a coarse screen for the arms 37 but in all instances the construction must be 30 such that the atomized fuel is heated to the proper temperature for vaporization without having its flow materially impeded.

The central part of the deflector 34 is threaded to receive the threaded part of the heat conducting member 35. The heat conducting member is provided with suitable arms 38 which extend into the combustion zone 14. The arms 38 are heated by the burning fuel and the heat is conducted to the deflector 34 and arms 37. The 40 amount of heat conducted to the deflector 34 and arms 37 is controlled by screwing the member 35 into or out of the deflector 34 and thereby decreasing or increasing the effective length of the heat conducting path between the arms 38 and 45 the deflector 34.

The combustion zone 14 where the vaporized fuel is burned, is separated from the chamber formed within the shell 32, by the screen 13. In a preferred modification the screen is a double 50 member consisting of a plate provided with small perforations and a woven screen of such mesh that the openings therein are larger than the perforations in the plate. This construction is illustrated in Figs. 1 and 2, where the perforated 55 plate is indicated at 39 and the woven screen is indicated at 40. Fig. 2 illustrates an additional feature of providing concentric corrugations in the woven screen 40. In some instances it may be found desirable to use the plain screen 40 of 60 Fig. 1 whereas in other instances it may be desirable to use the corrugated screen of Fig. 2.

The perforated plate 39 and the screen 40 are preferably supported by the member 12. Annular washers of suitable material such as asbestos are used to space the perforated plate and coarse screen from each other and from the heating arms 37. The coarse screen 40 is positioned between the heating arms and the perforated plate, and the spacing between the members is 70 preferably such that only a fraction of an inch separates the screen from the heating arms, and the perforated plate from the screen.

In a modified form of the burner the coarse screen 40 is provided with concentric annular 75

corrugations as shown in Fig. 2. In still another modification the perforated plate 39 and the coarse screen 40 are replaced by a single corrugated screen 41 such as is illustrated in Figs. 5 and 6. Various other modifications and substitutions may be made without affecting the operation of the burner.

The purpose of the perforated plate 39 and screen 40 is to conduct heat of combustion away from the under side of the combustion zone and thereby prevent backfiring into the vaporizing chamber. Any screen or perforated plate, or combination of screens and/or perforated plates which will successfully conduct the heat of combustion away from the combustion zone, and which will at the same time permit the unimpeded flow of heated, vaporized fuel therethrough, will be satisfactory for the purposes of the present invention. The construction illustrated in Fig. 1 is recommended as an approved form, however, because of its satisfactory operation and its comparatively low cost.

Locating the heater 12 adjacent the screen 13 and combustion zone 14 serves several useful purposes. In the first place it removes the heater from the vicinity of the atomizer nozzle and as a result the nozzle remains unheated. This prevents the formation of gum and carbon and other deposits at the nozzle and results in longer uninterrupted periods of operation of the burner. Another advantage of locating the heater near the combustion zone is that the vaporized fuel is burned before it has an opportunity to condense, for example, on the walls of the chamber housing the atomizer and associated structure.

In starting the burner the deflector 34 is preheated by suitable means such as the gas burner 42 or the electric heater 43. The gas burner 42 is burned steadily during the operation of the oil burner to provide a pilot light for insuring ignition of the vaporized fuel at all times. If found desirable suitable means may be provided for increasing the flow of gas from the burner 42 sufficiently to quickly heat conducting member 35 when the oil burner is to be started, and the flame from the burner 42 may be directed against the member 35 as indicated.

The electric heater 43 may be arranged as desired. A suitable construction comprises a number of turns of high resistance wire arranged in the deflector 34 as indicated in Figs. 1 and 2. Suitable leads are provided for supplying electric current at the proper voltage to heat the high resistance wire and consequently the heater 12 when it is desired to start the burner.

The heater 12 may also be preheated by burning suitable fuel such as alcohol or gasoline in the trough 44 formed in the deflector 34.

The oil burner is supplied with fuel from a suitable tank 50 through the fuel line 16. The fuel is introduced into the tank through an air tight valve 51. An air conduit or pipe 52 connects an air compressor 53 with the tank, and the air conduit 17 supplies air under pressure from the tank to the atomizer. Air conduits 17 and 52 are connected to the top of the tank whereas the oil pipe 16 is supplied with oil from near the bottom of the tank. Suitable valves are provided in the air conduits and the oil pipe.

Compressed air from the compressor 53 sets up a pressure in the air tight tank 50 which is transmitted to the oil and to the air supplied to the atomizer. Hence the oil and the air supplied to the atomizer are maintained at the same pressure regardless of what that pressure may be.

This arrangement eliminates the danger of setting up back pressure in either of the pipe lines 16 or 17 by shutting off the valve 27 in the atomizer, as would happen if the pressure in one of the pipe lines 16 and 17 exceeded the pressure in the other pipe line.

The fuel flowing in pipe line 16 passes through the automatic safety device 15. This device which is well known in the art, includes a valve that is normally held open and permits the fuel to flow therethrough. If the oil burner is not operating satisfactorily, oil from the atomizer will collect on the inclined plate 54 and flow down to the cup 55 which will drop down to the position indicated in dotted lines and permit the valve to close thereby shutting off the supply of fuel to the atomizer.

When the cup 55 drops to the position shown in dotted lines it completes an electric circuit and operates a solenoid 56 or some other suitable device, to close the valve 27. The valve 27 may also be operated by the manual control 57 shown in Fig. 4. When the electric circuit is completed a suitable alarm device such as the bell 58 is sounded to indicate that the burner has been automatically shut off because of improper operation.

The apparatus for atomizing and vaporizing hydrocarbonous fuels may also be used to provide vaporized fuels for use in internal combustion engines, gas turbines and various other types of apparatus requiring combustible vaporized fuels. The atomizing and vaporizing apparatus may also be used to provide vaporized fuels for illuminating purposes etc.

While I have shown only one approved form of burner and fuel supply system embodying the invention, it is to be understood that various modifications and changes may be made therein without departing from the spirit of the invention. It is, therefore, to be understood that I do not intend to be limited to the specific construction shown and described but only by the scope of the appended claims.

What I claim is:

1. In a hydrocarbon burner having a combustion zone, the combination of a fuel chamber, means separating said chamber from said combustion zone, a member in the fuel chamber for heating said fuel, and means for conducting heat from the combustion zone to said member, said heat conducting means including an adjustable member for controlling the heat conduction to the fuel heating member.

2. An oil burner comprising a fuel oil vaporizing chamber, structure defining a combustion zone in which the vaporized fuel is burned, and means for conveying heat from the combustion zone into the vaporizing chamber, said means including a member having a heat conducting part in the combustion zone, a heat radiating part in the vaporizing chamber, and adjustable screw means interconnecting the heat conducting part with the heat radiating part and permitting variation of the effective length of the heat conducting path therebetween.

3. A hydrocarbon burner comprising a fuel vaporizing chamber, structure defining a fuel burning zone, a screen separating said chamber from said zone, said screen having openings through which the vaporized fuel passes, a heat conducting member extending through said screen from said fuel burning zone into said chamber, and means for preheating said heat

conducting member before starting combustion of said fuel.

14. In a liquid fuel burner the combination of
an atomizer for atomizing the fuel, a chamber
into which the atomized fuel is directed, struc-
ture defining a combustion zone in which said
fuel is burned, a screen interposed in the path
of said atomized fuel, said screen separating the
first mentioned chamber from the combustion
zone, and a member extending from the combus-
tion zone through said screen into said chamber,
said member having a portion in the path of said
atomized fuel, said member conveying heat from
the combustion zone to vaporize the atomized
fuel.

18 fuel.

19 5. A hydrocarbon burner comprising means de-
20 fining a combustion zone, a chamber containing
fuel to be burned in the combustion zone, a
member separating the combustion zone from the
chamber containing the fuel to be burned, said
member comprising a screen having a coarse

mesh, a second screen having a fine mesh and means spacing said screens from each other to provide a narrow space therebetween, fuel heating means positioned in the fuel chamber and spaced from said screens, and means for transmitting heat from the combustion zone through said screens to said fuel heating means. 5

6. In a burner for hydrocarbonous fuels having a combustion zone and a zone in which small particles of the fuel are mixed with air and directed toward the combustion zone, the combination of a pair of members having openings therethrough, through which the fuel and air mixture passes before combustion, means supporting said members to separate the combustion zone from the fuel mixing zone, means spacing the members from each other to provide a narrow air space therebetween, a heat conducting member extending through the spaced members, and means for pre-heating the heat conducting member. 10 15 20
